COMBINATION LENS INDEXER AND MARKER

John T. Armbruster, Niagara Falls, N.Y., assignor to
American Optical Company, Southbridge, Mass.

Filed Sept. 12, 1960, Ser. No. 62,091

Term of patent 14 years

(Cl. D57—1)

Fig. 1

Fig. 2

Fig. 3

Fig. 4

FIG. 1 is a top plan view of a combination lens indexer and marker showing my new design;

FIG. 2 is a side elevational view thereof;

FIG. 3 is a rear elevational view thereof; and

FIG. 4 is a front elevational view thereof.

The side not shown is substantially the same as the side shown.

The cord is shown broken away in all the views of the drawing to indicate indeterminate length.

I claim:

The ornamental design for a combination lens indexer and marker, substantially as shown.
